UNITED STATES PATENT OFFICE.

KARL F. NYSTROM, OF CHICAGO, ILLINOIS.

CAR CONSTRUCTION.

Application filed April 19, 1924. Serial No. 707,570.

My invention relates more particularly to an improvement in refrigerator car construction and more especially to the method of construction whereby a steel frame car may be provided with suitable insulation and thereby utilized as a refrigerator car.

The invention has for its object the provision of a construction wherein a portion of the means employed for holding the insulation in place will also constitute means functioning as nailing strips to which the inside lining of the car may be secured; while the various bolts employed, whereby the steel posts or exterior braces are secured in place, are so arranged in the walls of the car as to permit a complete sealing of the bolt-heads and at the same time provide dead air space insulation.

The invention also has for its object a construction wherein the various wall elements consisting of cleats or sub-posts and girths are so arranged as to securely hold the pliable insulating material in place against sagging; the entire wall construction, including the roof and the floor being such that a complete insulating blanket is provided which affords continuous insulation at the side plates, namely at the sides and the ends of the car as well as across the top of the car.

The objects and advantages of my invention will be more clearly comprehended from the detailed description of the accompanying drawings, wherein—

Figure 1 is a vertical sectional view of a portion of a car, with intermediate portions broken away, illustrating my improved construction.

Figure 2 is a cross sectional view taken on the line 2—2 of Figure 1 looking in the direction of the arrows.

Figure 3 is a longitudinal sectional view of one end of a car, showing my improved wall construction, with a portion of the car shown broken away.

Figure 4 is a detail sectional view of the ceiling construction.

My invention contemplates the utilization of a steel frame car as a refrigerator car which, as exemplified in the drawings, comprises a suitable floor construction of sub-timbers with floor-boards as indicated at 10 all supported in the usual manner by the car-sills, one of which is shown at 11, to

which the steel posts or Z-bar braces shown at 12, as well as the corner plates or posts 13, are intended to be secured at their lower ends, while the upper ends thereof are secured to the angle members 14. The angle members 14 have the steel side plates 15 secured thereto, which, in turn, overlap the outer side of the outside sheathing 16; the sheathing 16 being preferably chamfered to receive the side plates as shown at 17. The outside sheathing 16, as clearly shown in Figure 1, extends to and rests on the side sills of the car underframe and the entire inner side of the outer sheathing is covered with suitable pliable insulating material 18 which is preferably arranged in double thickness or layers and preferably of continuous sheets as shown. The insulating material 18 is also preferably placed intermediate of the paper lining, indicated at 19, arranged along the inner side of the outer sheathing 16 and the inner sheathing or lining 20 extending from the upper edge of the topmost sheathing and the upper edge of an upper wooden girth 21 which is secured in place by the bolts which extend through the steel side plate and sheathing.

The car frame or wall construction also comprises a suitable number of wooden cleats or sub-posts 22 preferably arranged at equal distances apart and disposed from top to bottom intermediate of the outer sheathing 16 and the inside sheathing or lining 20 and bolted at top and bottom, with the bolt heads being preferably arranged as hereinafter described.

The wooden sub-posts 22 are formed to receive the horizontally disposed wooden girths 21 therebetween; the girths being arranged at different horizontal levels and spaced apart as shown in Figure 1.

The girths are secured in place by bolts, as at 23, which extend through the steel posts and outer sheathing. The heads of the bolts 23 are preferably countersunk in the girths 21; and before the bolts are put into place, the countersink is filled with a sealing compound, as for example an asphalt product, a portion whereof is drawn into the bolt-holes when the bolts are inserted, thus completely sealing the bolt-holes. The counter sinking of the bolts is done to such an extent that when the bolts are in place the heads, embedded in the sealing compound,

dead air space will be provided between the bolt-heads and the paper lining 19, as more clearly shown in Figure 2 at 24.

With all of the bolts, which secure the 5 girths and sub-posts in place, countersunk and the heads thereof inserted in and sealed with a suitable non-conducting compound and arranged to provide a dead air-space at the inner or head end of the bolts, a non- 10 heat conducting connection between the car exterior and its interior is provided.

The various girths and the sub-posts are utilized and arranged to hold the pliable insulating material, preferably hair felt, in 15 place and prevents the material from shifting or from sagging toward the bottom; while at the same time the girths and the sub-posts also constitute nailing strips for the inside paper lining and the inner sheath- 20 ing.

The side wall is provided with a meat-rail at 25, which is suitably bolted to the sub-posts and extends through the inner sheathing of the car.

25 The pliable insulating material,—in the form of continuous sheets,—is preferably arranged in at least two layers as shown and the sheets continued from the floor—where it is arranged between the sub-floor 26 and the main floor 10—upward along the side and end walls of the car and entirely across the top of the car, thus providing a complete blanket of insulating material extending through all parts of the car to the door- 30 posts on opposite sides of the door-opening; the sheet or one layer being preferably arranged that its meeting ends are off-set from or disposed at a different point from the meeting edges of the other sheet or layer as shown at 27 in Figure 1.

As shown in Figure 1, the insulating sheets continue from the side wall about the juncture of the side wall and car ceiling, with the insulation arranged between the blind 45 ceiling 28 and the inner or main ceiling 29.

The ceiling structure comprises the car-line 30,—which is secured to and supported by the angle members 14, and is preferably of inverted channel formation,—in which a 50 wooden sub-carline 31 is secured by means of bolts. The bolts which secure the sub-carline in place also constitute the means for holding suitable wooden cleats 32 in place; the cleats being disposed beneath the blind ceiling 28 and firmly hold the insulating material in proper place. These cleats 55 also constitute nailing strips for the main ceiling boards 29. I also prefer to provide the juncture between the sides and the top 60 of the car with a wooden fillet, as at 33 in Figure 1, to provide a tight juncture or corner.

As a result of my invention, a steel frame car may be utilized as a refrigerator car, 65 which is completely enveloped by a blanket

of suitable insulating material and wherein all bolts which extend from the car exterior are also completely sealed, with the result that a very efficient, thoroughly insulated refrigerator car is provided.

I have shown what I believe to be a simple embodiment of the invention, which has been described in terms employed merely as terms of description and not as terms of limitation, as structural modifications are 75 possible and may be made without, however, departing from the spirit of my invention.

What I claim is:

1. In a steel frame car provided with steel carlines, a blind ceiling and a main ceiling, spaced apart, and outer sheathing and inner sheathing spaced apart, insulating material disposed between the outer and inner sheathing, extending upward and continuing intermediate of the blind ceiling and the main ceiling, cleats suspended from the carlines, disposed beneath the insulating material and constituting nailing strips for the main ceiling, sub-posts and girths arranged between the insulating material and the inner sheathing, the sub-posts and girths being provided with bolt-head receiving sockets, bolts extending through to the car exterior for securing the sub-posts and girths in place, and a sealing medium for the heads of the bolts extending to the car exterior.

2. In a channeled steel frame car, provided with steel carlines, a wooden sub-carline suspended from and secured in a channel of the steel carline, a blind ceiling adjacent to 100 said wooden sub-carline, wooden cleats suspended from the composite carlines beneath the blind ceiling in spaced relation therewith, common means for suspending the wooden sub-carline and wooden cleats in 105 place, insulating material between the cleats and the blind ceiling, and a main ceiling secured to the cleats.

3. In a steel frame car provided with channel steel carlines, wooden sub-carlines 110 secured in the channels of the carlines, wooden cleats suspended from the carlines in spaced relation therewith, a blind ceiling secured to the bottom of the sub-carlines, a main ceiling secured to the bottoms of the 115 cleats, and insulating material disposed intermediate of the two ceilings and held against movement by said cleats.

4. In a steel frame car, steel carlines, 120 wooden sub-carlines secured to the carlines, wooden cleats disposed lengthwise of the carlines and suspended therebeneath, a blind ceiling secured to the bottoms of the wooden carlines, a main ceiling secured to the bottoms of the cleats, and continuous sheets 125 of insulating material between the two ceilings, extending down into the walls of the car, the sheets being held against shifting by the wooden cleats and blind ceiling.

5. In a steel frame car, provided with 130

- outer sheathing and inner sheathing arranged in spaced relation, steel carlines having fibrous sub-carlines secured thereto, a blind ceiling secured against the bottoms of 5 sub-carlines, a main ceiling suspended from the carlines, continuous sheets of insulating material extending from between the two ceilings down between the inner and outer sheathing, and means whereby shifting of 10 said sheets is prevented.
6. In a steel frame car provided with a double floor, a double ceiling, outer sheathing and inner sheathing arranged in spaced relation, sub-posts between the inner and 15 outer sheathing, girths arranged horizontally between the sub-posts, the sub-posts and girths having counter-sunk bolt-receiving openings, bolts whereby the sub-posts and girths are secured to the car outer frame, a 20 blanket of pliable insulating material disposed continuously between the double floor, about the juncture of floor and walls, upward about the juncture of the walls and ceiling and between the double ceiling, said 25 blanket being arranged between the outer sheathing and the sub-posts and girths, a paper lining between the girths and sub-posts and the inner sheathing, and a sealing
- medium for the heads of the bolts in said countersunk openings. 30
7. In a steel frame car provided with a spaced apart sub-floor and main floor, spaced apart inner and outer walls or sheathings and spaced apart blind and main ceiling, sheets of insulating material arranged 35 between the sub-floor and main floor extending about the juncture between the floor and car walls, intermediate of the inner and outer wall sheathing about the juncture of the walls and the ceiling and between the 40 blind ceiling and main ceiling so as to provide a continuous insulating blanket about the top, sides, ends and bottom of the car, with longitudinal wooden members disposed between the sub-floor and main floor 45 and between the blind ceiling and main ceiling for holding the insulating material in place and constituting nailing strips, and wooden members disposed vertically and horizontally intermediate of the wall sheathing, bolted to the steel frame members and car outer wall whereby the insulating material is held in place and nailing strips provided. 50

KARL F. NYSTROM.
